UNITED STATES PATENT OFFICE.

CLAUDE C. GOULD, OF BATAVIA, ASSIGNOR TO THE EASTERN ELECTRICAL MANUFACTURING COMPANY, OF WHEATFIELD, NEW YORK.

TELEPHONE-SWITCH SYSTEM.

SPECIFICATION forming part of Letters Patent No. 447,426, dated March 3, 1891.

Application filed October 10, 1887. Serial No. 251,885. (No model.)

To all whom it may concern:

Be it known that I, CLAUDE C. GOULD, of Batavia, in the county of Genesee and State of New York, have invented a new and useful Improvement in Telephone-Switch Systems, of which the following is a specification.

This invention relates to an improvement in that class of switch-board systems in which each subscriber's line is provided in the central office with a movable terminal, which is automatically moved out of its normal position, so as to break the connection with the ground, upon sending a current through the line.

The object of my invention is to provide a simple switch system of this kind whereby the connections between the subscribers can be effected expeditiously and with few movements.

My invention consists to these ends of the improvements which will be hereinafter fully described, and pointed out in the claims.

In the accompanying drawings, consisting of two sheets, Figure 1 is a vertical sectional elevation of my improved switch-board system. Fig. 2 is a horizontal section in line xx , Fig. 1. Fig. 3 is a vertical section of the movable switch-bar in line yy , Fig. 1. Fig. 4 is a sectional elevation in line zz , Fig. 1. Fig. 5 is a diagram of two switch-boards arranged side by side, showing the manner of connecting subscribers on different boards.

Like letters of reference refer to like parts in the several figures.

A represents the table portion, and A' the upright portion, of the switch-board, which is provided with sockets a , in which are arranged the subscribers' plugs B . Each socket a is provided with a spring a' , which bears against a contact-point b , arranged near the inner end of the socket when the plug B is seated in said socket. Above each subscriber's socket a is arranged a local outsocket c , which is connected with the subscriber's line D by a leg or wire c' .

E represents the annunciator, and E' the base thereof, which is secured to the upright portion A' of the switch-board. The annunciator E is connected with the subscriber's

instrument D' by the wire D and with a contact-point or spring e by a wire e' .

e^2 is a contact-spring bearing against the spring e and connected with the cord of the plug B by a wire e^3 . The contact-springs ee^2 are secured to a cross-piece e^4 , arranged in rear of the upright portion A' .

f is the apron of the annunciator E , which is pivoted at its lower end to the base E' and held in an elevated position by a hook or nose f' , formed at the outer end of the vibrating armature f^2 in a well-known manner. The apron f is provided below its pivot with a downwardly-projecting lip or tail-piece f^3 , which engages against the outer end of a horizontal locking-bolt G and moves the same inwardly when the apron f is released by the armature f^2 . The locking-bolt G is arranged in lugs g , formed on the under side of the base E' , and is moved outwardly by a spiral spring g' , interposed between the inner end of the base E' and a collar secured to the bolt G .

g^2 is a loop or link formed at the inner end of the sliding bolt G and projecting through an opening g^3 in the upright portion A' . The outward movement of the bolt is limited by the outer end of the link striking the lug e of the base E , as represented in Fig. 2.

H represents the vertically-movable switch-bar arranged on the rear side of the switch-board and moving in metallic brackets $h h'$, secured to the portion A' . The switch-bar H is provided near its upper end with a hook or nose h^2 , which engages with the rear cross-bar of the link g^2 and holds the switch-bar in an elevated position.

h^3 represents a spiral spring secured with one end to the switch-bar H and with its opposite end to an arm h^4 , formed on the upper bracket h , and whereby the switch-bar is drawn downwardly when released by the sliding bolt G . The arm h^4 is provided at its upper end with a guide-roller h^5 , which bears against the upper rear side of the switch-bar and assists in guiding the latter in its movements. When the apron f drops by the vibration of the armature f^2 , its lip f^3 strikes the outer inclined end of the locking-bolt G and causes the bolt to move inwardly, thereby dis-

engaging the link g^2 from the hook h^2 of the switch-bar and allowing the latter to descend. Upon raising the switch-bar H its hook h^2 engages in the link g^2 , and the spring g' draws the link outwardly and holds the same in engagement with the hook h^2 .

5 i is a cam or curved extension formed at the upper end of the switch-bar H above the hook h^2 , and which strikes the rear end of the sliding bolt G when the switch-bar descends and drives the sliding bolt outwardly against the lip f^3 with sufficient force to raise the apron f and cause the same to engage with the hook f' of the armature f^2 .

15 Each switch-bar H is provided with a button or knob j , which is visible to the operator, and whereby the operator can determine which switch-bar has fallen. The button j is secured to the lower end of the switch-bar H by a shank j' , which projects through a vertical slot j^2 in the board A' .

25 k is a wire connecting the upper metallic bracket h with the contact-point b , and k' is a wire connecting the lower metallic bracket h' with the ground. The two brackets h h' are connected by a metallic spring k^2 , secured to the switch-bar H and bearing against said brackets when the switch-bar is in an elevated position. In this position of the switch-bar

30 the circuit is closed and the subscriber is connected with the central office, the current passing from the subscriber's line D through the annunciator E , thence through the wire e' to the contact-springs e e^2 , thence through the wire e^3 to the plug B , from the latter through the spring a' , contact-point b , wire k , upper bracket h , spring k^2 , lower bracket h' , and finally to the ground through the wire k' . When the switch-bar H is in a depressed position, the spring k^2 is disconnected from the brackets h h' and the circuit is broken.

40 L is the operator's listening-telephone, which is connected with two contact-springs l l' by wires l^2 l^3 . The contact-springs l l' are secured to the cross-bar e^4 and are arranged in rear of the contact-springs e e^2 and in line therewith, as shown in Fig. 4.

45 M represents a switch-lever arranged below the switch-bar H and the contact-springs e e^2 l l' , and pivoted with its rear end to a cross-piece m and projecting with its front end through the slot j^2 .

50 The switch-lever M is constructed of suitable non-conductive material and provided on opposite sides with metallic contact-surfaces m' m^2 , which are separated from each other, as clearly shown in Figs. 1 and 4. Upon raising the lever M the contact-surfaces m' m^2 engage between the springs e e^2 and l l' 55 and separate the same. In this position of the lever the contact-piece m' connects the springs e and l , while the contact-piece m^2 connects the springs e^2 and l' , thereby causing the current to pass through the wires l^2 l^3 60 and looping the operator's telephone into the circuit. The free ends of the contact-springs e e^2 and l l' are bent outwardly, and the me-

tallic contact-surfaces of the lever M are V -shaped to facilitate the entrance of the switch-lever between the contact-springs. When released, the switch-lever is returned to its depressed position by a spiral spring m^3 . The switch-lever M is arranged directly below the switch-bar H , so that the latter rests upon the switch-lever when in its lowest position and is raised by the upward movement of the switch-lever.

70 N represents the generator, which is connected with the ground by a wire n and with a contact-point n' , arranged near the inner end of the outsocket c , by a wire n^2 .

75 o is a flat contact-spring arranged within the outsocket c and connected with the wire c' . The spring o is so arranged that its free inner end will not be raised sufficiently to come in contact with the contact-point n' in the normal position of a plug placed in the socket c , but will merely bear against the plug. When it is desired to connect the generator with the main line, the handle of the 85 plug seated in the outsocket c is depressed, so as to raise the inner end of the plug and press the inner end of the spring o against the contact-point n' . The socket c is made somewhat larger than the plug to permit of 90 this movement of the plug.

95 P represents a metallic socket secured in the upright portion A' of the switch-board and provided with a contact-spring P' , which is connected by a wire p with a contact-spring p' on the rear side of the switch-bar H of the same subscriber's annunciator, located on a different switch-board, as indicated in Figs. 1 and 5.

100 P^2 is a wire which connects the generator with a contact-point P^3 , arranged near the inner end of the outsocket P .

105 p^2 p^3 represent two contact-points secured to a cross-bar p^4 above and below the contact-spring p' . The contact-point p^2 is connected 110 with the main line D by a wire p^5 , and the contact-point p^3 with the line e' by a wire p^6 .

115 When the switch-bar H is in an elevated position, the spring p' bears against the upper contact-point p^2 , and when the bar is in a depressed position the spring p' bears against the lower contact-point p^3 .

120 Each switch-board is provided with as many local outsockets c as there are subscribers arranged on said switch-board and with as many outsockets P as there are subscribers connected with the other switch boards or sections in the same exchange.

125 In making a connection between two subscribers located upon the same board or section, the operation is as follows: When the subscriber calls the central office, the vibration of the armature f^2 releases the apron f , which causes the sliding bolt G to release the switch-bar H and allow the same to descend, thereby disconnecting the contact-spring k^2 130 from the brackets h h' and breaking the circuit. The calling subscriber can now no longer ring his bell, and from this fact he

ficiently to permit their hooks h^2 to engage in the loops g^2 of the locking-bolts, and hence the switch-bars again descend, thereby replacing the aprons without interfering with the connected subscribers. When the subscribers ring off, the aprons of both subscribers drop, and this notifies the operators that the subscribers have finished. The switch bars of both subscribers are now again raised, so as to replace the fallen aprons and restore the lines to their original condition ready for another call.

I claim as my invention—

1. The combination, with the annunciator and its apron, of a locking-bolt actuated by the falling of the apron, and a movable switch-bar engaging with said locking-bolt and adapted to replace the fallen apron when disengaged from said locking-bolt, substantially as set forth.

2. The combination, with the annunciator and its apron, of a locking-bolt actuated by the falling of said apron, and a movable switch-bar engaging with said locking-bolt and provided with a cam which strikes the locking-bolt when the switch-bar descends and replaces the fallen apron, substantially as set forth.

3. The combination, with the apron f and the locking-bolt G , of a movable switch-bar H , provided with a hook or nose engaging with said locking-bolt, and with a cam i , arranged above said hook or nose, which moves the locking-bolt forwardly when the switch-bar descends, substantially as set forth.

4. The combination, with the apron f and the locking-bolt G , of a movable switch-bar H , provided with a hook or nose engaging with said locking-bolt, a cam i , arranged above said hook or nose, which moves the locking-bolt forwardly when the switch-bar descends, and an incline q , formed at the upper end of the switch-bar, and whereby the locking-bolt is moved forwardly and the apron is replaced

when the switch-bar is raised, substantially 45 as set forth.

5. The combination, with the locking-bolt G and the movable switch-bar H , of a switch-lever M , arranged below the switch-bar and adapted to raise the latter for engaging the locking-bolt with said switch-bar, while at the same time looping in the operator's listening-telephone, substantially as set forth.

6. The combination, with the switch-bar H , of the contact-springs $e e^2 l l'$, listening-telephone J , and a switch-lever M , whereby the listening-telephone is looped into the circuit and the switch-bar is elevated upon raising the lever M , substantially as set forth.

7. The combination, with the contact-points $p^2 p^3$, connected with the main line, of a switch-bar H , provided with a contact-point p' , adapted to engage alternately with the contact-points $p^2 p^3$, and an outsocket P , connected with the contact-point p' , substantially as set forth.

8. The combination, with the locking-bolt G and the switch-bar H , of the contact-points $p^2 p^3$, connected with the main line, a contact-spring p' , attached to the switch-bar and adapted to engage with the contact-point p^2 when the switch-bar is in a normal position and with the contact-point p^3 when the switch-bar is in an abnormal position, substantially as set forth.

9. The combination, with two or more sections or tables, of a switch-lever H and contact-points $p' p^2 p^3$, arranged upon one section, and an outsocket P , arranged in some other section and connected with the contact-point p' , substantially as set forth.

Witness my hand this 20th day of September, 1887.

CLAUDE C. GOULD.

Witnesses:

JNO. J. BONNER,
FRED. C. GEYER.

knows that his call has been received at the central office. The subscriber's call is made known to the operator by the descent of the signal j . The operator now raises the switch-lever M , thereby raising the switch-bar H and restoring the circuit and at the same time looping in his listening-telephone L . This movement again engages the bar H with the sliding bolt G . When the operator has ascertained with whom the calling subscriber wishes to be connected, he allows the switch-lever to descend and places the calling subscriber's plug B into the outsocket c of the called subscriber, whereby the two subscribers are connected. By thus removing the plug B from the socket a the calling subscriber's ground is broken at the central office by the spring a' moving away from the contact-point b . The two subscribers are now connected by the current passing from the calling subscriber's line D to and through the annunciator E , wire e' , contact-springs e^2 , wire e^3 , plug B , contact-spring o of the socket c , and wire c' to the called subscriber's line D . When the connection between the two subscribers has been effected, the operator depresses the handle of the calling subscriber's plug seated in the called subscriber's outsocket, thereby pressing the contact-spring o against the contact-point n' and connecting the generator N and ringing the bells of both subscribers simultaneously, thus notifying them that they have been connected. He then allows the inner end of the plug to descend, so as to disconnect the spring o from the contact-point n' and cut out the generator.

When the generator is connected on the circuit, the plug D is held in contact with the generator contact-point long enough to call up both subscribers. As this interval is longer than that required for the switch-bar to descend, the armature of the calling subscriber is caused to vibrate after the switch-bar has fallen and the apron has been operated by the sliding bolt. This continued vibration of the armature prevents the apron from engaging with the hook of the armature, and the latter consequently drops again, whereby the locking-bolt is moved inwardly, as above described, and held in this position by the lip f^3 of the apron bearing against the front inclined end of the bolt. This connection with the generator also causes the current to overflow the line D of the called subscriber and vibrate the armature of the called subscriber's annunciator, thereby releasing the switch-bar H and breaking his ground at the central office. The descending movement of the called subscriber's switch-bar H causes the locking-bolt G to again replace the fallen f , as before described.

In order to enable the operator to determine when the subscribers have rung off, it is necessary to again raise the switch-bar of the calling subscriber and replace his fallen

apron. For this purpose the switch-bar is provided above the cam i with an incline g , which engages in its upward movement against the rear end of the locking-bolt G , thereby moving the latter forwardly and again elevating the apron.

When the subscribers ring off, the calling subscriber's armature f^2 is again vibrated, the apron drops, and the switch-bar, with its signal, descends, thus notifying the operator that the subscribers have finished. The operator now raises the switch-bars of both subscribers, whereby the lines are restored to their original condition ready for another call.

If a subscriber is wanted whose terminal is located on some other section or table, the operator inserts the plug B of the calling line into the socket P of the called line. The subscribers are now connected through the calling subscriber's line D , wire e' , and plug B , as above described, contact-spring P' , wire p , contact-spring p' of the called subscriber's switch-bar H , contact-point p^2 , wire p^3 , and called subscriber's wire D . The operator now loops in his listening-telephone L by raising the lever M and ascertains whether the called line is engaged. If the operator finds that the called line is engaged, he withdraws the plug B without interference with the called line. If the operator finds the called line to be disengaged, he depresses the plug B in the outsocket P , so as to connect the contact-spring P' with the generator, thereby calling both lines simultaneously. The operator now allows the rear end of the plug to descend, so as to disengage the generator from the line. By connecting the main line with the generator the switch-bars H of both subscribers are allowed to descend, thereby disengaging the contact-spring p' from the upper contact-point p^2 and connecting the same with the lower contact-point p^3 . The calling subscriber is now connected with the called subscriber by the plug B , as above described, outsocket P , contact-spring P' , wire p , contact-spring p' of called subscriber's switch-bar H , lower contact-point p^3 , wire p^6 , wire e' , called subscriber's annunciator E , and wire D . This connection with the generator causes the armatures f^2 of both annunciators to vibrate longer than the interval required by the switch-bar to descend, as hereinbefore described, thereby allowing the aprons to drop and remain in this position. This position of the apron on the section or table on which the called subscriber is arranged notifies the operator on said section that the subscriber has been called by an operator on a different section. The operators in charge of the tables upon which the two subscribers are located now give the hand-levers M a short and quick upward movement, so as to cause the cams g at the upper end of the switch-bars to move the locking-bolts G outwardly and replace the aprons. This short movement of the levers does not, however, raise the switch-bars suf-
